Application February 13, 1933, Serial No. 656,612
In Germany February 17, 1932

7 Claims. (Cl. 158—117.1)

The present invention relates to improved gas heating appliances, in which there is provided a back-draught safety device in which the waste gases dammed-back and returning due to back-draught operate safety devices, which effect the closing of the main gas valve, arranged in advance of the burner. It has already been proposed to provide a back-draught safety device in which the returning waste gases due to a back-draught are conducted to a guardian flame, which controls the main gas valve—for example, by thermostatic means—by the main valve being held open by the burning guardian flame, whilst it automatically closes on the extinction of the guardian flame. If a back-draught occurs, the guardian flame becomes extinguished owing to the deficiency in oxygen of the waste gases supplied to it, so that the main valve automatically closes. By this means the main burner is also extinguished and the production of further quantities of waste gases is prevented.

In this proposal, however, both the waste gases ascending from the main burner and the waste gases returning from the outlet pipe are conducted to the guardian flame. This arrangement has the drawback that in a back-draught caused by strong wind too much fresh air from the chimney might be contained in the waste gases flowing back from the outlet pipe, so that the guardian flame was not extinguished quickly enough.

The invention relates to an improvement in this back-draught safety device, and consists in that the waste gases to be supplied to the guardian flame—the extinguishing gases—are taken only from the current of waste gases coming from the main burner, and in fact at a place where the gases from the burner have a strong upward movement, and where on the damming back or return flow an excess pressure occurs, thus, for instance, a little above the air damper openings of the draught hood or outlet conduit. By this arrangement it is possible to take a partial current from the burner waste gases poor in oxygen, which fully suffices to extinguish the guardian flame very quickly and with certainty. The effect of this arrangement can be considerably improved if the pipe is cooled in which the current of extinguishing gas taken from the current of burner waste gases is conveyed. In the cold pipe the extinguishing gases are rapidly cooled and descend by their own weight in the pipe to the guardian flame to be extinguished. Consequently, only a quite small force is necessary to introduce the waste gases into the pipe, because the descending cold extinguishing gases exert a suc-

tion action on the upper end of the descending pipe which facilitates the entrance of the waste gases. The arrangement, in fact, comes into operation so easily that it is necessary in certain circumstances to provide retarding means to prevent a too frequent extinction of the guardian flame, for instance, during short gusts of wind. The employment of a branched extinguishing gas pipe makes it particularly simple to make the action of the extinguishing gases on the guardian flame dependent in a quite definite manner on the duration and strength of the back-draught. In order to delay the action of the back-draught on the guardian flame, it suffices to provide one or more enlargements in the extinguishing gas pipe leading from the outlet pipe to the guardian flame, so that the waste gases forced during a back-draught into the extinguishing gas pipe must first fill these enlargements before they can reach the guardian flame. By making the enlargement of a suitable size the duration or strength of the back-draught can be exactly determined at which an extinction of the guardian flame, and thus a shutting off of the main burner, shall occur. If, on the other hand, it is desired to increase the speed of response of the protective device, a guide surface may be arranged above the inlet opening of the extinguishing gas pipe by which the waste gases returning from the outlet pipe which are strongly mixed with air and thus are rich in oxygen are led off, and are, for instance, conducted away through the draught hood, whilst the waste gases which are poor in oxygen coming from the main burner are held back, as under a roof, so that they pass more easily into the extinguishing gas pipe.

Several examples of construction of the invention are shown in the drawings, in which—

Figures 1 and 2 are diagrams of a liquid heater having a guardian flame safety device, showing normal draught and in the case of a back draught, respectively.

Figure 3 shows the same arrangement with a guide plate inserted.

Figure 4 is a diagram of a gas heating stove having a pilot flame safety device.

Figure 5 is a vertical section through a bathroom geyser having a retarded back-draught safety device, but with certain interior parts shown in side elevation.

Figure 6 is a rear elevation of the geyser shown in Figure 5, with the back wall removed.

Figure 7 is a partial sectional view on an enlarged scale of a modified form of the guardian flame burner shown in Fig. 5 and showing in side

elevation the connection of the extinguishing gas pipe with the guardian flame burner.

In the liquid heater shown in Figures 1 to 3, the liquid is heated in the heat-exchanging device 10. A draught hood 12 having an outlet pipe 13 is provided above the combustion chamber 11; 15 are air damper or draught-reducing openings at the bottom of the hood. It is to be understood, of course, that the outlet pipe 13 is connected to the flue or chimney of the building or room in which the heater is located, and under normal draft conditions there will be an up draft through the combustion chamber 11, the draft hood 12, the outlet 13, and the flue or chimney 15 of the building. Under this normal draft condition, air enters through the bottom opening 15 of the hood and so dampens the updraft through the combustion chamber as to prevent excessive amounts of cold air being drawn through that chamber which would unduly cool its walls and thereby diminish the heating effect of the main gas burner. A main gas pipe 18 leads above a main gas valve 23 to the main burner 16. The diaphragm 24 of this main gas valve has a throttle opening 25 through which a weak current of control-gas flows constantly from the high pressure side 26 into the controlling chamber 27. From the controlling chamber 27 a gas pipe 28 leads to the burner 29 of a guardian flame, which acts on a thermostatic valve 32 controlling the control-gas pipe 28.

In the example of construction shown, the guardian flame burner 29 is formed as a safety pilot burner, and in fact by the burner casing 29 being closed by a thermostat disc 30, which contains a burner opening 31 and carries a valve plate 32. If the thermostat disc 30 is cold, it presses the valve plate 32 on its seat and thereby closes the outlet of the control-gas pipe 28, so that the control-gas collects in the control chamber 27 of the main valve and presses the diaphragm 24 against the main valve seat (Figure 3). If, however, the thermostat disc 30 is heated by a flame, for example, the guardian flame, it curves or bends upwardly and opens the valve 32, so that the pressure escapes from the control chamber 27 and the main gas valve opens. This guardian flame, whose burner may, of course, be of a different construction, is so arranged that it lies in the path of the extinguishing gases and is extinguished by them.

In front of the outlet pipe 13 a pipe connection 43 branches off and extends downwardly outside the waste gas conduit of the heat-exchanging device 10 into immediate proximity to the guardian flame. While not essential, it may be advantageous to cover this pipe with heat insulating material as a protection against absorption by the descending gases of heat through the metal wall of the pipe from the room outside. With normal draught, the waste gases take their way from the burner chamber 11 through the draught hood 12 and the outlet pipe 13 into the chimney (Fig. 1). When a back-draught occurs (Fig. 2), the waste gases ascending from the burner 16 into the outlet pipe 13 encounter a column of waste gas and air which conflicts with their ascent. Consequently, an excess pressure occurs in the draught hood 12, which tends to force the waste gases through its bottom openings 15 into the room where the appliance is situated. A part of the waste gases penetrates at the same time into the extinguishing gas pipe 43 and arrives at the pilot burner 29, the guardian flame of which becomes extinguished in the waste gases

which are deficient in oxygen (Fig. 2). After the extinction of the pilot flame the thermostat disc 30 becomes cold, and at once presses the valve plate 32 on its seat, whereby the control-gas pipe 28 is closed and the main valve is closed in the manner already described, so that the gas jets of the main burner 16 are extinguished (Fig. 3). It is preferable to place the inlet of the extinguishing gas pipe 43, 44 as high as possible above the air damper opening of the draft hood, 10 so that on a back-draught the rising current of the gas column between that opening and the branch pipe 43 for the extinguishing gas is sufficiently great to force the waste gases into the extinguishing gas pipe 43. 15

In the liquid heater shown in Figure 3 a guide plate 45 directed obliquely downwards is arranged above the inlet opening of the extinguishing gas pipe 43. The guide plate 45 catches the waste gases poor in oxygen rising from the burner 16 and holds them back in front of the extinguishing gas pipe 43. The waste gases returning from the chimney and mixed with air are prevented, on the other hand, by the plate 45 from entering into the pipe 43 and are conducted to the bottom 25 opening of the hood.

In the gas heating stove shown in Figure 4, the main gas pipe 18 is closed by a thermostat valve 46 when the stove is out of use. If the diaphragm of the valve is heated by a pilot flame directed against it, the valve 46 opens the gas passage and gas flows to the main burner 16. The burnt gas rises upwards in the heating bodies 47 and escapes through the outlet pipe 48. From the outlet pipe 48 an extinguishing gas pipe 43, 35 as before, leads to the pilot burner 29. On a back-draught, the pent up waste gases pass into the pipe 43 and flow in it to the pilot flame, which is put out and thereby effects the closing of the thermostatic main gas valve 46. In the extinguishing gas pipe 43 a box-shaped enlargement 49 is provided, in which the downwardly-flowing extinguishing gases first collect before they reach the pilot flame. The pilot flame is thus prevented from becoming immediately extinguished at every brief back-draft, for example, during short gusts of wind.

It is further to be noted that in the Fig. 4 construction the discharge-end portion of the pipe 43 is formed as a mouth-piece fitting over the pilot burner 29 so that when a sufficient back-draught pressure occurs in the discharge flue 48 to cause a flow of waste gases from that flue through the pipe 43 and its enlargement 49, the outlet mouth-piece of the pipe 43 discharges those gases 55 directly over the outlet orifice or jet of the pilot burner. The outlet mouth-piece on the discharge end of pipe 43 of the Fig. 4 construction is the same as the outlet mouth-piece on the discharge end of the waste-gas pipe shown in Fig. 7 later 60 to be referred to.

The geyser shown in Figure 5 has the usual construction of a through-flow heater to be suspended on the wall. 10' is the heat-exchanging device and 12' the draught hood, which are both 65 enclosed by a sheet metal outer casing 50, provided with the air-damper openings 15'. 13 is the outlet pipe for the waste gases. The cold water passes through pipe 51 through a valve 52 into a tubular worm 53 and is there heated by the 70 ascending hot gases. The gas flows from the main gas pipe 18 through a main gas valve 23 to the main burner 16. The pilot flame is here also used as the back-draught safety device. The extinguishing gas pipe 43 in this case again 75

branches from the draught hood 12', which pipe is a descending pipe 44 leads inside the sheet metal outer casing 50 to the automatic safety pilot burner 29. A flat box-shaped receptacle 49' is interposed in the descending pipe 44, and is surrounded by the casing 50. When a back-draught occurs in the outlet pipe for the waste gases, a rise in pressure occurs in the draught hood 12' due to the hot burner gases. Consequently, a part of the waste gases poor in oxygen is forced into the extinguishing gas pipe 43 and conducted downwards by the descending pipe 44. In order to strengthen the downward flow of the extinguishing gases in the descending pipe 44, the descending pipe and the enlargement 49' are separated by a partition wall 58 from the adjacent interior portion of the casing 50 containing the heat-exchanger 10'. The partition wall 58 is to keep off the heat from the extinguishing gas pipe 13, 44 and the receptacle 49' interposed therein. A special cooling arrangement (water or air) may also be provided for the extinguishing gas pipe 43, 44 and the receptacle 49' interposed therein. The waste gases quickly cool in the cold pipe and receptacle rapidly descend therein and thereby exert a suction action on the waste gases flowing back from the draught-interrupting hood 12'. When the extinguishing gases have extinguished the pilot flame, the diaphragm 30 of the pilot burner 29 closes the pilot valve 32, and pressure occurs in the control chamber 21 of the diaphragm valve 23 which presses the diaphragm 24 against the gas outlet and closes it.

Figure 7 shows on a larger scale a modified form of the safety pilot burner 29 of the Figs. 5 and 6 construction having a releasable connection with the waste gas pipe 43, 44 and an additional gas supply pipe for initial ignition purposes. Fig. 7 also shows a mouth-piece on the discharge-end portion of the waste-gas pipe the same as the mouth-piece employed on the discharge-end portion of the waste-gas pipe 43 in the Figs. 4, 5, and 6 constructions. The valve casing 29' is secured to the additional gas-supply pipe 59 of the pilot burner, and is closed by a diaphragm 30 provided with a burner opening 31. 32 is a valve member, which, when the pilot flame is out, is pressed by the diaphragm 30 by the intermediary of a spring 61 on the valve seat 60. The controlling gas reaches the valve by a pipe 28 as in the Fig. 5 construction. When the diaphragm 32 is heated by a flame, it curves upwardly, raises the valve 32 from the seat 60, and allows the controlling gas to flow out. 63 is an opening through which a current of ignition gas can be sent through the pipe 59 to the burner opening 31 by by-passing the closed valve 32, in order to form an ignition flame. A flexible metal pipe 64 is provided for releasable connection with the end of the extinguishing gas pipe 43, 44 shown in Fig. 5, and this flexible pipe 64 terminates in a mouth-piece 65. This mouth piece 65 is formed like a lid or cover which extends over the valve casing 29' of the pilot valve and closes it with the exception of an opening 67 opposite the burner opening 31 in the cover-plate 66 of the mouth-piece. A space is left between the cover-plate 66 and the diaphragm 30 through which the extinguishing gases can flow from all sides to the burner opening 31 and escape through the opening 67. In this way the pilot flame passing through the cover opening 67 is extinguished with quickness and certainty without affecting the flames of the main burner, which continue to burn undisturbed until the main gas valve 23

(shown in Fig. 5) is closed owing to the extinction of the pilot flame in the manner already several times described.

The thermostatic disc employed in all the examples of construction of the invention may be either a bimetallic or a single metal disc, as desired, but preferably, and as shown for the thermostatic disc 30 in Figs. 1 to 3, inclusive Figs. 5 and 7, and for the thermostatic disc 46 in Fig. 4, this element is a single metallic sheet.

While the part of the apparatus indicated at 12 in Figs. 1, 2, and 3, and 12' in Figs. 5 and 6, specifically functions as a draught hood, and has been termed a draught hood in the foregoing part of the specification, and the part 13 has hereinbefore been referred to as an outlet pipe from that hood, that hood and pipe also constitute a flue leading from the combustion chamber or casing of the main gas burner.

We declare, that what we claim is:

1. A safety gas appliance comprising a casing having a main gas burner, a flue leading from said casing, a pilot burner positioned to ignite said main burner, gas-supply conduits leading to said burners, a cut-off valve in the main-burner-supply conduit, means including means responsive to the heat of the pilot burner operative to maintain said cut-off valve open when the pilot flame is on and to close the same upon extinguishment of the pilot flame, and means opening into said flue and terminating adjacent said pilot burner and operating to extinguish the pilot flame upon an increase in gas pressure in said flue due to a back draught therein.

2. A safety gas appliance comprising a casing having a main gas burner, a flue leading from said casing, a pilot burner positioned to ignite said main burner, gas-supply conduits leading to said burners, a cut-off valve in the main-burner-supply conduit, means including means responsive to the heat of the pilot burner operative to maintain said cut-off valve open when the pilot flame is on and to close the same upon extinguishment of the pilot flame, and conduit means opening into said flue and terminating adjacent the jet of said pilot burner and operating to discharge a flame-extinguishing stream of waste gas against said jet upon an increase in gas pressure in said flue due to a back draught therein, said conduit means comprising means operating to retard the speed of flow of the waste gases therethrough below the speed of backflow of gases in said flue.

3. A safety gas appliance comprising a casing having a main gas burner, a flue leading from said casing, a pilot burner positioned to ignite said main burner, gas-supply conduits leading to said burners, a cut-off valve in the main-burner-supply conduit, means including means responsive to the heat of the pilot burner operative to maintain said cut-off valve open when the pilot flame is on and to close the same upon extinguishment of the pilot flame, and conduit means opening into said flue and terminating adjacent the jet of said pilot burner and operating to discharge a flame-extinguishing stream of waste gas against said jet upon an increase in gas pressure in said flue due to a back draught therein, said conduit means comprising a pipe having a portion intermediate its length of enlarged diameter and a contracted terminal or discharge-end portion.

4. A safety gas appliance comprising a casing having a main gas burner, a flue leading from said casing, said flue comprising a draught hood for said casing having walls upwardly converging

- ing to a restricted outlet aperture for said hood, a pilot burner positioned to ignite said main burner, gas-supply conduits leading to said burners, a cut-off valve in the main-burner-supply conduit, means including means responsive to the heat of the pilot burner operative to maintain said cut-off valve open when the pilot flame is on and to close the same upon extinguishment of the pilot flame, and conduit means opening 5 into said hood in the region of minimum cross-sectional area thereof adjacent said outlet aperture and terminating adjacent the jet of said pilot burner and operating to discharge a flame-extinguishing stream of waste gas against said jet 10 upon an increase in gas pressure in said flue due to a back draught therein.
5. A safety gas appliance as defined in claim 4 and in which said conduit means has its open connection with said hood downwardly adjacent 15 said outlet aperture and said hood is provided intermediate said outlet aperture and said hood with baffle means adapted to direct upflowing waste gases from said main gas burner into said conduit 20 means upon an increase of gas pressure in said flue due to a back draught therein and to deflect down-flow back-draught gases away from said 25

open connection or inlet end of said conduit means.

6. A safety gas appliance comprising a casing having a main gas burner, a flue leading from said casing, a pilot burner positioned to ignite said main burner, gas-supply conduits leading to said burners, a cut-off valve in the main-burner-supply conduit, means including means responsive to the heat of the pilot burner operative to maintain said cut-off valve open when the pilot flame 10 is on and to close the same upon extinguishment of the pilot flame, and conduit means opening into said flue and having as its terminal portion a mouth-piece fitting over said pilot burner with said mouth-piece provided with an outlet opening 15 for the waste gases and pilot flame whereby said conduit means operates to discharge a flame-extinguishing stream of waste gases against said jet upon an increase in gas pressure in said flue due to a back-draught therein. 20

7. A safety gas appliance as defined in claim 6 and further characterized by said mouth-piece having a rim detachably mounting said mouth-piece on said pilot burner over the pilot jet. 25
